UNITED STATES PATENT OFFICE

126,199

DESIGN FOR A KEY CHAIN OR SIMILAR ARTICLE

Ralph E. Daniels, Miami, Fla., assignor to Swank,
Inc., a corporation of Delaware

Application September 27, 1940, Serial No. 95,432

Term of patent 14 years

To all whom it may concern:

Be it known that I, Ralph E. Daniels, a citizen of the United States of America, residing at Miami, county of Dade, State of Florida, have invented a new, original, and ornamental Design for a Key Chain or Similar Article, of which the following is a specification, reference being had to the accompanying drawing, forming a part thereof.

The figure is a perspective view of a key chain or similar article showing my new design.

The dominant feature of my design resides in the hook portion shown in full lines assembled in a key chain as illustrated.

I claim:

The ornamental design for a key chain or similar article, substantially as shown and described.

RALPH E. DANIELS.
